United States Patent Office

Des. 183,197
Patented July 15, 1958

183,197

TROPHY BASE

Ray E. Dodge, Miami Beach, Fla., assignor to Dodge,
Inc., Chicago, Ill., a corporation of Illinois

Application August 16, 1957, Serial No. 47,385

Term of patent 14 years

(Cl. D29—23)

FIG. 1

FIG. 2

FIG. 3

*Fig. 1*Figure 1 is a front elevational view of a trophy base, showing my new design;

Fig. 2 is a side elevational view;

Fig. 3 is a top plan view; and

Fig. 4 is a front perspective view thereof with the base and cover portion being omitted for convenience of illustration.

The dominant feature of my design resides in the portion shown in full lines.

I claim:

The ornamental design for a trophy base, as shown and described.
